UNITED STATES PATENT OFFICE.

WILLIAM M. HAYWARD, OF NATICK, MASSACHUSETTS.

FUEL SAVER.

Application filed April 26, 1923. Serial No. 634,666.

To all whom it may concern:

Be it known that I, WILLIAM M. HAYWARD, a citizen of the United States, residing at Natick, in the county of Middlesex and State of Massachusetts, have invented new and useful Improvements in Fuel Savers, of which the following is a specification.

This invention relates to fuel savers of that type designed to introduce heated air into the combustion chamber of a furnace or hot water or steam boiler and comprises a construction whereby highly heated air is admitted and directed in films or layers, one close to the surface of the fuel to cause combustion of gases distilled off by the incandescent body of fuel therebeneath, and one into the upper portion of the combustion chamber, this latter acting to break up and form a combustible mixture with the gases thrown off in great quantities from fresh fuel just after its application to the fire, this combustible mixture being ignited by the flame from the lower flame layer which acts as a pilot light.

By the use of flat jets the air is directed well into the fire box where it is most effective, it having been found in practice that a nozzle forming a jet of small size can project the air only a very short distance within the combustion chamber without the use of excessive pressure differences within and without the nozzle. So far as I am aware prior devices intended for the purposes of this invention have been made of cast metal which is of considerable thickness and weight and when carried by the furnace door are clumsy and subject the doors and their mountings to severe strain as the doors are opened and closed. Furthermore the thickness of the walls of such cast metal devices acts to delay the conduction of heat resulting in great differences of temperature between its inner and outer surfaces so that the air is inadequately heated by the time it is admitted to the combustion chamber.

These difficulties have been overcome in the present invention by constructing the device of sheet steel, producing a comparatively light weight device capable of quickly transmitting heat to the air passing therethrough. While the device becomes very hot, in practice it has been found that the

air passing therethrough is sufficient to prevent burning or other injury because of the high temperature. 55

The device of the present invention is also so designed that little adjustment is ever necessary, and that which it is desirable to make, as when changing fuels as from hard to soft coal, may be made by simple tools by an unskilled person.

For a more complete understanding of this invention reference may be had to the accompanying drawings in which

Figures 1 and 2 are perspectives of the device detached showing opposite ends thereof.

Figure 3 is a fragmentary cross section through a domestic hot air furnace showing in section the device in operative position.

Figure 4 is a fragmentary view in perspective showing the device attached to the inner face of the fire door. 75

Referring to these figures it will be seen that the device comprises a sheet metal casing having upper and lower walls 1 and 2 arranged in substantially parallel spaced relation, these walls being joined at their side edges by side plates 3 which converge toward each other away from the open end 4 of the casing. The walls 1, 2, and 3 may be made integral and formed by bending sheet material of the proper size and shape, the ends of the sheet as shown being brought together and lapped in a seam 5. At 6 is shown a reentrant angle wall forming the inner end of the casing joining the side walls 3 and forming therewith and with the top and bottom walls 1 and 2, a pair of spaced substantially flat nozzles 7 through which heated air may pass from the interior of the casing into the combustion chamber as shown by the arrows in Figure 3. This casing is designed to be made fast to the inner face of a fire door as shown at 10 in Figures 3 and 4, the fire door being provided with one or more air openings 11 in the usual manner through which air may enter the casing to be heated and then projected into the combustion chamber as above noted. 100

Any suitable means may be provided for attaching the casing to the door, but as shown one or more bolts 12 may be employed 105 extending from the outer face of the door and through the apex 9 of the reentrant angle wall 6 beyond which it may receive a

nut 13 by which the casing may be drawn back against the inner surface of the fire door. It will be noted from the drawing that the apex 9 at the rear of the reentrant angle wall 6 is positioned somewhat closer to the lower wall 2 than to the upper wall 1. This causes a greater volume of air to be passed through the upper nozzle 7 than through the lower nozzle. The air passing through the lower nozzle as shown is directed closely against the upper face of the fuel bed so as to unite with the gases distilled off therefrom and form therewith a combustible mixture which is ignited by the fire. This nozzle projecting sufficiently far into the combustion chamber so that it is maintained highly heated by the combustion of the fuel so that when the air is admitted to the combustion chamber through the nozzle it is in condition to be readily ignited. The gases evolved from the fuel are thus largely consumed adjacent the surface thereof, the gases and air forming a combustible mixture adjacent the surface of the fuel over a large area thereof, the air being admitted in a substantially flat sheet or layer which is able to pass well within the combustion chamber without excessive pressure due to a heavy furnace draft. The gases and air from the lower nozzle therefore perform their function as long as any gases are evolved from the fuel and act as a pilot light to ignite gases driven off in considerable volume from fresh fuel when this is applied to the fire. When fresh fuel is applied these gases which escape unburned from the field of action of the lower nozzle are broken up and thoroughly mixed with air passing through the upper nozzle 7 so that they form a combustible mixture which is immediately ignited by the flame adjacent the lower nozzle. This construction of the casing affords an extended heating surface for the nozzles and is of sheet metal of such thickness that the heat conduction is very rapid. The device is also of comparatively light weight so that no severe strains are imposed on the door or its mountings when the door is opened or closed.

It has been found in practice that the pipe damper employed between the check draft and the chimney may be nearly closed without causing an accumulation of gas to be formed in the combustion chamber immediately after fresh fuel is supplied which ordinarily would be liable to cause an explosion therein. The gases given off are burned within the combustion chamber and are not permitted to escape as combustible gases or be thrown off and produce injurious fumes in the surrounding atmosphere.

When fuel such as hard coal is employed the nozzles may be made comparatively narrow by partially closing them by the use of pliers, bringing the upper and lower walls

and the reentrant wall 6 at the nozzle openings comparatively near together, while when soft coal is being employed these nozzles may be made wider by suitably bending the material. In use the inner end of the casing and the nozzles become very hot but it has been found that the air passing therethrough is sufficient to prevent burning or other injury to the nozzles by this extreme heat. As the combustible gases driven off from the fresh fuel by the incandescent fuel therebeneath are thus consumed in the furnace, the heat derived from this combustion is utilized and the production of smoke and the throwing off of deleterious combustible gases is effectually prevented.

Having thus described an embodiment of this invention it should be evident to those skilled in the art that many changes and modifications might be made therein without departing from its spirit or scope as defined by the appended claims.

I claim:

1. A device of the class described comprising a casing for attachment at its open outer end to the inner face of a fire door, said casing having substantially horizontal upper and lower walls, side walls, and an inner end wall formed as a reentrant angle portion joining said side walls and forming therewith and with said upper and lower walls a pair of horizontally disposed flat nozzle openings.

2. A device of the class described comprising a casing for attachment at its open outer end to the inner face of a fire door, said casing having substantially parallel upper and lower walls, converging side walls, and an inner end wall formed as a reentrant angle portion joining said side walls and forming therewith and with said upper and lower walls a pair of horizontally disposed flat nozzle openings, the apex of said reentrant angle portion being closer to said lower than to said upper wall to cause a larger proportion of air entering said casing through said door to escape through said upper nozzle.

3. A device of the class described comprising a casing for attachment at its open outer end to the inner face of a fire door, said casing having substantially parallel upper and lower walls, converging side walls, and an inner end wall formed as a reentrant angle portion joining said side walls and forming with said upper and lower walls a pair of horizontally disposed flat nozzle openings, and means passing through the apex of said reentrant angle portion for attaching said casing to said door.

4. A device of the class described comprising a sheet metal casing having substantially parallel upper and lower walls, side walls joining said upper and lower walls and converging toward one end there-

of, a reentrant angle end wall positioned between said side walls at said converging end and spaced from said upper and lower walls to define therewith a pair of spaced horizontally disposed narrow slots through said end, and means for fixing said casing with its opposite open end against the inner face of a furnace door.

5. A device of the class described comprising a sheet metal casing having substantially parallel upper and lower walls, side walls joining said upper and lower walls and converging toward one end thereof, a reentrant angle end wall positioned between said side walls at said converging end and spaced from said upper and lower walls to define therewith a pair of spaced horizontally disposed narrow slots through said end, said reentrant angle portion being closer to said lower than to said upper wall and means for fixing said casing with its

opposite open end against the inner face of a furnace door.

6. The combination with a furnace having a combustion chamber, and a door for closing an opening into said chamber through which fuel may be supplied thereto, said door having openings therethrough, of a casing having upper and lower and side walls and an inner end wall formed with a reentrant angle and defining with said upper, lower and side walls a pair of spaced nozzles, and means engaging the reentrant angle portion of said end wall and said door for fixing said casing to said door with the outer edges of said upper, lower and side walls against the inner face of said door and enclosing said door openings.

In testimony whereof I have affixed my signature.

WILLIAM M. HAYWARD.
